UNITED STATES PATENT OFFICE.

WALTER WRIGHT, OF NEW YORK, N. Y., ASSIGNOR TO UNDERWOOD COMPUTING
MACHINE COMPANY, OF NEW YORK, N. Y., A CORPORATION OF NEW YORK.

COMBINED TYPE-WRITING AND COMPUTING MACHINE.

1,274,971.

Specification of Letters Patent.

Patented Aug. 6, 1918.

Application filed September 18, 1912. Serial No. 720,914.

To all whom it may concern:

Be it known that I, WALTER WRIGHT, a citizen of the United States, residing in New York city, in the county of New York and State of New York, have invented certain new and useful Improvements in Combined Type-Writing and Computing Machines, of which the following is a specification.

This invention relates to computing machines, and is especially adapted to be used in a combined typewriting and computing machine.

In said combined machines, the numeral keys are usually arranged to operate either themselves or through a power attachment, computing wheels, and in whatsoever method this is done, the computing attachment affects to some degree the touch of the typewriter keys. In some forms of mechanism, even when power-driven, the touch of such numeral keys is very much harder than that of the remaining keys of the typewriter, and in any key-driven one, however lightly it may have been constructed and designed, the additional inertia of the computing mechanism is bound to add something to the load in operating its keys, and so handicap the operator both in speed and in comfort.

The present invention is described to overcome this and other difficulties. It is here-with disclosed as applied to an Underwood typewriter having a Wright key-driven typewriter attachment. The keys in themselves may bear precisely the same relation to the computing mechanism as ordinarily built. When, however, a numeral key is depressed, according to the present invention, a power mechanism is arranged to be ordinarily brought into play to take some or all of the load off the finger of the operator which is pressing the key. The power mechanism for accomplishing this, preferably is in the form of a constantly driven motor. A power shaft, geared to said motor is preferably arranged to carry driving members adjacent to the numeral keys or adjacent to links connected to them in such a manner that after a numeral key is somewhat depressed, the driving-member will pick up the key or its link and automatically complete the movement of said key. This power driving-member preferably is in the form of an arm which is arranged to

strike and force downward a lug depending from a numeral key. This lug preferably rides in a cam which, toward the end of the stroke of the key, guides the lug out of the path of the driving-member, and at the very end of the stroke a cam on the driving-member will swing the lug to start the key on its return stroke.

Preferably the computing mechanism is so arranged with reference to the numeral keys, that the beginning of the stroke of the numeral key is almost or entirely unaffected by the computing mechanism, but later when the computing mechanism begins to be affected by the computing key, the power-drive will take hold of the computing key and assist the operator as above described.

Other features and advantages will hereinafter appear.

In the accompanying drawings,

Figure 1 is a side view largely diagrammatic of an Underwood typewriting machine having a Wright key-driven attachment to which my invention has been applied.

Fig. 2 is a similar front view of the same.

Figs. 3 and 4 show views of the numeral key driving link from opposite sides and its relation to some other parts.

Figs. 5 and 6 show diagrammatically the relation of the driving-member to the numeral key lug and the cam which drives it.

Numeral keys 1 and letter keys 2 depress key-levers 3 to swing type-bars 4 through bell cranks 5 upwardly and rearwardly against a platen 6 so that type 7 print against said platen. Said platen is mounted in a carriage 8 which is drawn forward in letter-feeding direction by means of a spring not shown, and is controlled in said letter feeding by means of an escapement wheel 9 carrying a ratchet 10 working in a rack 11 connected to said carriage. Said escapement wheel is controlled by dogs 12, 13, which are arranged to alternately engage it, and are operated by means of a universal member 14 pivoted on a rock arm 15 and operated through a segment 16 from heels 17 in the type-bars.

As said carriage 8 travels along in its letter-feeding movement, it carries along with it by means of an arm 18, a totalizer 19, said totalizer comprising dial wheels 20,

which by said letter-feeding movement are arranged to be engaged *seriatim* to be turned by means of a master-wheel 21. Said master-wheel in the present instance is arranged to be turned in a manner to be described later, by means of links 22 extending upwardly from the numeral keys, there being one link for each numeral key, and the connection being such that the master-wheel will be turned in proportion to the numeral key being operated.

For the purpose of assisting the keys by means of power, each numeral key-lever has depending therefrom, a link 23 pivoted on the lever at 24, and each link carries at its lower end a lug 25. As the numeral key is depressed, said lug 25 is guided around in a cam 26, so as to bring said lug into the path of a constantly driven arm 27 which will strike said lug, as seen in Fig. 4, and drag said key-lever downwardly thereby. Said power-driven arm 27, of which there is one for each numeral key, as seen in Fig. 2, is fast on a shaft 28 journaled on the side frames of the typewriting machine, and said shaft is power-driven, and for this purpose carries at one end a bevel gear 29 meshing with a bevel gear 30 fast on the axle 31 of a constantly driven electrical motor 32.

Each lug, as has been said, is guided in a cam 26, and said cam is in the form of a groove sloping from the top down toward the power-driven arm 27, so that when the numeral key 1 is depressed, said lug will travel toward the path of said power-driven arm. For the purpose of making said lug travel more easily in said direction, a spring 33 extends to the link 23 and is anchored in the key-lever 3 so as to draw said link rearwardly. When said link has been moved as above described, into the path of the power-driven member 27, it reaches a part of the cam groove which extends practically straight downward and, later, when the key is near the bottom of its stroke, as seen in Fig. 4, reaches a part of the groove which extends forwardly until the point of the lug is reached where the key reaches the bottom of its stroke. At this point, the groove extends forwardly and upwardly, and is so arranged to guide the lug 25, that is drawn onto the cam 35 formed on the end of the driving-member 27 thereby causing said cam to force said lug forwardly and upwardly to some extent, as seen in Figs. 5 and 6, until said link is drawn upward with the key-lever by means of a returning spring 36, which normally holds said key-lever in its normal position. Said groove cam 26 is so arranged, as said lug rises in it, to guide the lug rearwardly as it approaches the top bringing the lug again in position to be guided rearwardly and downwardly on the next stroke of the key-lever. Said groove

cam 26 is preferably given some freedom to move so as to relieve the rigidity of the structure. For this purpose said groove cam 26 is formed in a member 37, slidably pivoted on a fixed rod 38 in the frame of the machine. Said sliding motion is permitted by means of a vertical slot 39 in which said fixed rod plays. The lower end of said member 37 carries a guiding pin 40, which is guided in a slot 41 extending upwardly and rearwardly in a swinging arm 42 pivoted on the swinging arm of said frame at 43. Said arm is normally drawn upwardly by means of a spring 44, which will yield and permit cam member 37 to be carried downwardly to some extent against the tension of said spring 44 if the driving-member 27 happens to strike the cam member 37, so as to move said cam member downwardly. There are preferably formed for each numeral key-lever, two driving-members 27 on the shaft 28, so that twice in each revolution of the shaft 28, the numeral key-lever may be dragged down if operated.

The computing mechanism proper is preferably formed so as to be operated only after the numeral key 21 has been noticeably depressed. For this purpose, the link 22 may be arranged to move downwardly a segment 45 comprising a toothed-portion 46 and a toothless-portion 47. Said toothless-portion 47 normally stands in engagement with the gear wheel 48, which is connected to drive the master wheel, and the toothless surface forms a Geneva lock with the gear wheel 48, thus normally locking said gear wheel 48. When, however, said numeral key has been depressed, say one-third of its stroke, the tooth-portion 46 of said segment 45 engages with said wheel 48 so as to positively turn it. Said segment 45 also comprises a second toothless-portion 49 arranged to form a Geneva lock to positively arrest said wheel 48 after it has been turned by said toothed-portion 46, and so positively arrest said master-wheel. In this way, any overthrow of the computing mechanism due to over rapid action of the numeral key 1 is positively prevented. The group of segments taken together form an indexing mechanism for driving the computing wheels.

Said segment may likewise comprise a full-stroke mechanism comprising a ratchet 50 and a pawl 51, so as to prevent any incomplete action of any numeral key. Thus it will be seen that the beginning of the stroke of any numeral key is practically precisely like that of any other key, that after said stroke has been well begun, the computing mechanism comes actively into play, but about the same time or perhaps a little sooner, the power-member 27 begins to drive the numeral key by engaging

the lug 25 and thus relieve the finger of the operator from any load the computing mechanism may tend to throw onto it.

It will be also observed that the numeral key is not positively arrested at the bottom of its stroke, but that the connection through the cam-member 37 is sufficiently loose to allow some variation in throwing due to looseness in construction or wear in the various parts.

In the computing mechanism herein illustrated, the segment 45 turns the master-wheel 21 through an intermediate shaft 52, and the dial wheel 20 is turned by the master-wheel 21 through an idle wheel 53.

Variations may be resorted to within the scope of the invention, and portions of the improvements may be used without others.

Having thus described my invention, I claim:

1. In a combined typewriting and computing machine, the combination of computing mechanism and typewriter numeral keys, connections between said numeral keys and computing wheels so arranged that each key moves free of connection with said computing mechanism during the first part of its down stroke, but moves in connection with said computing mechanism during the remainder of its down stroke, a source of power, a connection between each key and said source of power arranged to pick up each key at the time said key is connected with said computing mechanism and finish the operation of a key to drive said computing mechanism.

2. In a combined typewriting and computing machine, the combination with computing wheels and numeral keys, of a link depending from each numeral key, a lug on each link, a cam in which each lug is guided, and a resilient member supporting said cam.

3. In a combined typewriting and computing machine, the combination with computing wheels and numeral keys, of a master wheel driven by said numeral keys and adapted to engage said computing wheels *seriatim* to turn them, a type-bar connected to each numeral key, a link connected to each numeral key, a lug on each of said links, a cam by which said link is guided, a power-driven member adapted to strike said lug and carry it along when said lug has passed part way along said cam, an extension on said cam adapted to guide said lug out of the path of said driven member, and a cam on said driven member adapted to force said lug along said cam extension.

4. In a combined typewriting and computing machine, the combination with numeral keys and computing wheels, of a master wheel driven by said keys and adapted to engage said computing wheels *seriatim* to turn them, a type-bar con-

nected to each numeral key, a link connected to each numeral key, a lug on said link, a cam by which said link is guided, a power-driven member adapted to strike said lug when said lug has passed part way along said cam, an extension on said cam adapted to guide said lug out of the path of said power-driven member, a cam on said power-driven member adapted to force said lug along said cam extension, and a yieldable member supporting said link-guiding cam.

5. In a key-driven computing machine the combination with computing mechanism and numeral keys, of a source of power for driving said computing mechanism through said keys, said source of power being normally ineffective on said keys and said keys being normally ineffective on said computing mechanism and means acting on the depression of a numeral key and acting during the early part of the stroke thereof to connect said source of power to said key and at substantially the same time to connect said key and said computing mechanism so that the source of power drives the key during the entire computing stroke thereof to thereby relieve the key of any work of driving the computing mechanism.

6. In a combined typewriting and computing machine, the combination with computing wheels and numeral keys, of a master wheel driven by said keys and adapted to engage said computing wheels *seriatim*, a link connected to each numeral key, a lug on each link, a cam in which each lug is guided, a resilient member supporting said cam, a power-driven member for driving said keys by said links to an extent determined by their cams, and type-bars connected to said keys adapted to print at the end of a key stroke.

7. A computing machine having a constantly driven power-member and a continuous grooved cam for controlling the connection between the computing keys and the power.

8. A computing machine comprising a power-driven member constantly rotating, a link arranged to move the computing mechanism, a key-lever forming part of the connection between said member and said mechanism, and a cam for moving said link as said key-lever is depressed to bring said link into the path of said member.

9. In a computing machine the combination with a power-driven member, of a numeral key, a lug depending from said key, an arm on said power-driven member to strike said lug, a continuous cam comprising a groove having an elongated path, a point at each end thereof, a flat portion intermediate said ends, and a pin traveling in said groove to carry said lug into the path of said power-driven member at the beginning

120

125

130

- of a key depression and out at the end of the key depression.
10. In a combined typewriting and computing machine, the combination with numeral keys and computing wheels, of a master wheel driven by said keys and adapted to engage said wheels *seriatim* to turn them, a type-bar connected to each numeral key, a link connected to each numeral key, a lug 10 on each of said links, a cam for guiding each lug, a power-driven member adapted to engage any lug to cause it to travel along its cam and be carried out of the path of said power-driven member, a spring normally holding said link, so that said lug will travel into the path of said power-driven member, and a resilient member for holding said cam in position.
11. In a combined typewriting and computing machine, the combination with numeral keys and computing wheels, of a master wheel driven by said numeral keys and adapted to engage said computing wheels *seriatim* to turn them, a link connected to each numeral key, a lug on said link, a cam in which said link is guided, a power-driven member adapted to strike said lug when said lug has passed part way along said cam, an extension on said cam adapted to guide said lug out of the path of said driven member, and a cam on said driven member adapted to force said lug along said cam extension.
12. In a combined typewriting and computing machine, the combination with numeral keys and computing wheels, of a master wheel driven by said keys and adapted to engage said wheels *seriatim*, a link connected to each numeral key, a lug on each of said links, a cam in which each lug travels, a power-driven member adapted to engage any lug to cause it to travel in said cam and be carried out of the path of said member, a spring normally holding each link so that each lug will travel in the path of said driven member, and resilient means for holding said cam in position.
13. In a computing machine, the combination with a constantly rotating member, of computing wheels, a key lever forming part of the connection between said member and said wheels, a link on each key lever, a type bar connected to said key lever, and a cam for moving said link as said key lever is depressed to bring said link into the path of said member.
14. In a combined typewriting and computing machine, the combination with numeral keys and computing wheels, of an extension on each numeral key for turning said computing wheels, type bars also connected to said numeral keys, a power-driven member, a cam effective at the operation of each numeral key to bring its extension into the path of said power-driven member, and a cam on said power-driven member for

making the connection between said member and said extension ineffective.

15. In a computing machine, the combination with computing wheels and a power-driven member, of a lug adapted to be moved by said power-driven member to turn a computing wheel, means for guiding said lug into the path of said power-driven member, an arm forming part of said power-driven member which engages said lug, and a cam forming part of said arm for moving said lug beyond the path of said arm when said lug has been moved a predetermined amount by said arm.

16. In a computing machine, the combination with computing wheels and a power-driven member, of a lug, an arm forming part of said power-driven member, means for moving said lug into the path of said power-driven member to turn a computing wheel, means for moving said lug out of the path of said power-driven member when it has moved a predetermined amount, and a connection between said lug and the computing wheel moved thereby adapted to complete the turning of said computing wheel before said lug has been completely so moved by said power-driven member.

17. In a computing machine, the combination with computing wheels and a power-driven member, of a lug, an arm forming part of said power-driven member, means for moving said lug into the path of said power-driven member to turn a computing wheel, means for moving said lug out of the path of said power-driven member when it has moved a predetermined amount, a connection between said lug and the computing wheel moved thereby adapted to complete the turning of said computing wheel before said lug has been completely so moved by said power-driven member, a cam for guiding said lug, and means for holding said cam yieldably so as to permit said lug to move idly to some extent if moved by said power-driven member.

18. In a computing machine, the combination with a power-driven member and computing wheels, of a lug for turning a computing wheel when struck by said power-driven member, a cam for guiding said lug into and out of the path of said power-driven member, a slidably pivoted plate carrying said cam, and a lever to which said cam is slidably pivoted releasably holding said cam in position.

19. In a combined typewriting and computing machine, the combination with a row of keys and key levers on which they are mounted, of a type bar connected to each key lever, a power-driven shaft beneath said key levers and adjacent to them, a lug connected to each key lever, an arm on said power-driven shaft for each key lever, means for moving said lugs into the path of said

arms for causing said key levers to compute and print, and cams on said arms for moving said lugs to ineffective positions.

20. In a combined typewriting and computing machine, the combination with a bank of typewriter printing keys including manually operable alphabet and numeral keys, of a source of power, computing wheels adapted to be driven by said numeral keys, means for connecting said power to said numeral keys by the depression of said numeral keys, a swinging cam for each numeral key for so connecting it, and a lug for each key operated by its cam to disconnect said keys from 15 said source of power.

21. The combination with a bank of typewriter printing keys including keys operating alphabet and numeral printing types, of a source of power, computing wheels, means for operating said types manually by 20 said keys, means for connecting said numeral types to said source of power by ini-

tial manual movement thereof, means for connecting said power-driven types to said wheels, a swinging cam for each numeral 25 key, a follower for said key in its cam for so connecting it, and a lug connected to each key and operated by its cam to disconnect said type from said power.

22. In a combined typewriting and computing machine, the combination with alphabet and numeral keys, of a source of power, means for connecting said power to said numeral keys and not said alphabet keys, a swinging cam for each numeral key, 30 a lug for each key operated by its cam to disconnect said keys from said source of power, computing wheels driven by said power-operated keys, and means for preventing overthrow of said computing wheels. 35 40
